Primary Examiner — Joseph Kukella*Assistant Examiner* — Heather Wencl(74) *Attorney, Agent, or Firm* — Demian K. Jackson; Jackson IPG PLLC**CLAIM**

The ornamental design for a main body of seat belt adjuster, as shown and described.

DESCRIPTION

FIG. 1 is a top perspective view of a main body of seat belt adjuster showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines, shown in the drawings, indicate portions of the main body of seat belt adjuster which form no part of the claimed design.
